SUPPORT FOR ELECTRIC HAND MIXER OR THE LIKE

William F. Liatti, 1807 Fernridge,
San Dimas, Calif. 91773

Filed Mar. 24, 1969, Ser. No. 16,394

Term of patent 14 years

Int. Cl. D7—99

U.S. Cl. D44—29

The figure is a perspective view of a support for an electric mixer or the like showing my new design.

I claim:

The ornamental design for a support for electric hand mixer or the like, substantially as shown.
